UNITED STATES PATENT OFFICE

CHARLES P. SCHLEGEL, OF ROCHESTER, NEW YORK, ASSIGNOR TO THE SCHLEGEL MANUFACTURING COMPANY, OF ROCHESTER, NEW YORK, A CORPORATION OF NEW YORK

WINDOW CHANNEL

Application filed November 14, 1927, Serial No. 233,161. Renewed January 18, 1932.

The present invention relates to window channels and particularly to the type designed for use in the window frames of automobiles and other places where it is desirable to maintain a weather tight connection between the sash and the frame as well as to prevent the rattling of the sash in the frame, this application being a continuation in part of an application filed by me on Feb. 16, 1925, Serial No. 9,405, and of my companion application Serial No. 233,162, filed on the same date herewith. An object of this invention is to provide a construction which is inexpensive to manufacture and which has long life. Another object of the invention is to provide a construction which will make it possible to eliminate the use of rubber, felt and other similar resilient materials which tend to harden quickly. A further object of the invention is to provide a construction which will make it possible to depend solely on the surface of a textile fabric for obtaining the resiliency necessary to exclude the weather and prevent rattling of the sash so as to obtain longer life in the window channel.

To these and other ends, the invention consists of certain parts and combinations of parts all of which will be hereinafter described: the novel features being pointed out in the appended claims.

In the drawings:

Figs. 1 and 2 are respectively plan and edge views of one embodiment of the fabric used in the channel;

Figs. 3 and 4 are similar views of another embodiment of the fabric;

Figs. 5 and 6 are similar views of still another embodiment of the fabric;

Fig. 7 is a transverse section through a window channel utilizing the fabric illustrated in Figs. 1 and 2;

Fig. 8 is a transverse section of a window channel utilizing the fabric used in Figs. 3 and 4;

Figs. 9 and 10 are transverse sections through two different embodiments of the invention both employing the fabric illustrated in Figs. 5 and 6;

Figs. 11 and 12 are two views of another embodiment of the invention employing a

ductile stiffening means and the fabric shown in Figs. 5 and 6, Fig. 11 illustrating the materials before they are bent into channel form and Fig. 12 showing the materials in channel form; and

Figs. 13 and 14 are views of still another embodiment employing the fabric shown in Fig. 6, the stiffening means being in the form of two separate members forming parts of the side walls of the channel, Fig. 13 showing the position of the parts before they are bent into channel form illustrated in Fig. 14.

Prior to this invention, it has been suggested to employ in window channels yielding or resilient material which will act as a sound preventer and a weather excluder. Materials most generally employed are rubber and felt. Rubber quickly hardens and deteriorates while felt has short life, due to its becoming packed and hardened. In both instances, the material is expensive. Woven fabric has been used in connection with these materials but merely as a covering means therefor. According to this invention, the relatively heavy woven fabric, as described in my said prior application Serial No. 9,405 has a relatively soft cushion surface such as a long pile surface which acts as a cushion, preventing the rattling and at the same time excluding bad weather and cold air. The fabric is so supported in those portions forming the side walls of the channel that the pliability or flexibility of the fabric is destroyed except in the cushion surfaces which becomes the sole cushioning means for the sash. The fabric is preferably woven in strip form in such a manner that it is particularly adapted for window channels. Preferably it has selvaged edges which prevent the unravelling of the material in use, and breaks are provided in the cushion surface permitting the strip to be readily folded into channel form.

Various modifications of the form of the textile fabric as well as the stiffening means therefor are contemplated. Herein are shown and described a number of modifications but it is apparent that many more are possible.

In Figs. 1 to 6 inclusive, three embodi-

ments of the textile fabric are shown. In Figs. 1 and 2, a woven textile strip is employed which has selvaged edges 1 to keep the strip from unravelling, a central portion 2 which provides a break between the pile or cushion surfaces 3 arranged on opposite sides of the central portion. In the embodiment shown in Figs. 3 and 4, the selvaged edges 1 are present, and the central portion is a pile or cushion surface 2^a with parallel longitudinally extending breaks 2^b separating the portions 2^a from the cushion or pile portions 3. In the embodiments shown in Figs. 5 and 6, the fabric is the same as shown in Figs. 3 and 4 except that two wide longitudinally extending breaks 4 are provided beyond the cushion or pile surfaces 3.

One manner of using the textile fabric, as illustrated in Figs. 1 and 2, is shown in Fig. 7, the fabric being bent or folded as at 5 at the junctions between the sides of the break 2 and the cushion or pile surfaces 3, being arranged in a channel member 6 formed of rigid or unyielding material, such for instance, as sheet metal, or other suitable material, and being secured by any suitable means on the inner faces of the channel which is then placed in the frame 7 and receives the sash 8.

30 In the embodiment shown in Fig. 8, the fabric illustrated in Figs. 3 and 4 is secured in the channel member 6 in the same manner as illustrated in Fig. 7, the fabric being bent at the breaks 2^b.

35 In the embodiment shown in Fig. 9, the fabric illustrated in Fig. 6 is used in connection with a channel member 6, like that employed in Figs. 7 and 8. The fabric, in this instance, not only covers the inner faces of the channel member 6 but the break portions 4 are extended over the outer faces of the side walls and the outer face of the bottom wall of the channel member 6, an adhesive or other means being employed for securing the 45 fabric to the channel member.

In the embodiment shown in Fig. 10, the fabric illustrated in Figs. 5 and 6 has its breaks 4 folded at 9 to overlap the rear faces of the other portions of the fabric and the 50 breaks 4 are held in this position by stitches 10 which pass through the breaks 2^b. The structure is then bent on the lines of the stitches and is inserted in a channel member 6^a formed of sheet metal and having over- 55 hanging retaining lips 6^b which engage the fabric at the folds 9 holding the fabric in the channel member. The channel member is formed from sheet metal and provides an unyielding supporting surface for the textile 60 fabric.

In the embodiment illustrated in Figs. 11 and 12, the form of the textile fabric illustrated in Figs. 5 and 6 is employed. A filler in the form of a strip 11 of lead or other 65 soft substantially incompressible material

has the fabric folded about it while said strip is in a flat condition as illustrated in Fig. 11, the break portions 4 of the fabric lying on one side of the strip 11 while the pile portions 2^a and 3 lie on the opposite side. Stitches 12 70 are passed through the fabric and the metal, preferably in two parallel lines arranged at the breaks 2^b. This secures the fabric to the filler which, being ductile, is readily bent to the form shown in Fig. 12, along longitudinal 75 lines intersecting the breaks 2^b.

Figs. 13 and 14 illustrate another manner of using the fabric strip illustrated in Fig. 6. In this construction two thin strips 13 of metal or other substantially incompressible or unyielding material are provided for strengthening the side walls only of the channel. These strips abut the fabric on the sides opposite the sides provided with the pile surfaces 3 and the break portions 4 are folded 80 around the edges of the strip 11 to lie on the opposite side of said strips 13. Stitching 14 is then passed through the breaks 2^b and through the breaks 4 on the inner edges of the strips 13. The structure is then folded into 85 channel form as illustrated in Fig. 14 and placed in the channel of the frame in which the sash is mounted.

It will be seen from the foregoing that fibre or fingers project substantially at right angles 90 to the inner faces of a channel's side walls which are made of incompressible or unyielding material. These fingers are assembled in dense relationship so that they act as lateral supports for each other and are of such a 100 length that they form a cushion which will hold the sash or window out of contact with the unyielding or incompressible side walls of the channel, thus making it possible to do away with the rubber and felt as a cushioning means. Not only do the fibres or fingers act as cushions but they also serve to produce an antifriction surface to keep the sash or window from binding in the channel.

As shown and described, the supporting or 110 reinforcing means such for example as the channel member 6 or strips 11, are substantially spaced from the window sash or glass 8, leaving the relatively long pile fibers to occupy such spaces between the supporting or 115 reinforcing means and the glass which not only affords substantial resilient cushioning means for the glass and reduces its sliding friction, but has the additional advantage of accommodating a considerable variation in 120 thickness of the sash or glass such as results, for example, from the usual variation in thickness in the run of the glass, as well understood in the art.

What I claim as my invention and desire to 125 secure by Letters Patent is:

1. A window channel having rigid side walls and a woven textile covering and having a woven body portion extending over the inner faces of the bottom and the side walls 130

- of the channel, and cushioning anti-friction surfaces on those portions of the woven body portion covering the inner faces of the side walls of the channel, said surfaces being formed by stiff cushion-forming pile extending substantially at right angles to the inner faces of the side walls of the channel, and having such a density that the fibres act to support each other laterally to maintain substantially the right angle relationship to the side walls, the woven body portion being free of pile adjacent the corners between the side walls and the bottom wall so that a compression of the pile at the corners due to bending 10 the covering to fit within the channel does not take place.
2. A window channel comprising substantially rigid supporting means and a combined cushioning and friction reducing body supported thereby of relatively heavy fabric bent into channel shape and woven to provide the inner faces of the sides of the channel with relatively long densely arranged pile fibers projecting at substantially right-angular relation to said fabric body for engagement at their ends with the window glass to afford substantially resilient and friction reducing surfaces for maintaining effective cushioning support on which the glass readily slides.
3. A window channel embodying a strip of woven textile material having pile cushion surfaces, two longitudinally extending inner portions free from pile separating said cushion surfaces, and two marginal portions free from pile beyond said cushion surfaces, the edges of the strip being bent on the rear side of the strip and secured to the main body of said strip at the said inner pile free portions.
4. A window channel embodying a strip of woven textile material having selvaged edges, pile cushion surfaces, longitudinally extending portions free from pile adjacent said selvaged edges and beyond the pile cushion surfaces lying on the rear side of the strip and secured to the main body of the strip.
5. A window channel embodying a strip of woven textile material having selvaged edges, three pile cushion surfaces, two longitudinally extending portions free from pile separating said pile cushion surfaces, and two longitudinally extending portions free from pile beyond said cushion surfaces lying on the rear face of the strip and secured to the main body of the strip.
6. A window channel embodying a strip of woven textile material having three pile cushion surfaces, two longitudinally extending portions free from pile separating said surfaces, said woven strip having its marginal edges folded on the back of the strip and secured to the main body of the strip.
7. A window channel comprising a woven strip of textile material formed with pile cushion surfaces for cooperating with the opposite faces of a sash movable in a channel, and two separate strips of incompressible material supporting the textile material against flexing in the side walls of the channel.
8. A window channel comprising two separate strips of incompressible material forming parts of the side walls of the channel, and a strip of woven textile material bent into channel form and having its side walls supported by said two separate strips against flexing, said textile material having pile cushion surfaces on the portions supported by the strips for cooperating with opposite faces of the sash.
9. A window channel comprising a strip of woven textile material having two spaced pile cushioned surfaces and portions free from pile adjacent the margin of the strip bent on the rear face of the main portion of the strip and secured to the strip between the two cushioned surfaces, and two strips of incompressible material each arranged between a marginal portion of the strip free from pile and a portion provided with a pile cushioned surface.
10. A window channel comprising two separate strips of incompressible material forming parts of the side walls of the channel, and a strip of woven textile material having two portions provided with pile cushioned surfaces abutting the inner faces of the incompressible strips, said strip of woven textile material also having marginal portions free from pile lying on the outer faces of the incompressible strips and secured to the strip of woven textile material between the portions of said strip provided with the pile cushioned surfaces.
11. A window channel comprising a strip of woven textile material having three spaced pile cushioned surfaces, two inner portions free from pile between said pile surfaces and marginal portions free from pile beyond said surfaces, the marginal portions free from pile being bent on the rear face of the main portion of the strip and secured to the main portion of the strip at the two inner portions free from pile, and two separate strips of incompressible material arranged between the marginal portions free from pile and the rear face of the main portion of the textile strip.
12. A window channel comprising supporting side walls substantially spaced from the window sash and provided on their inner faces with relatively long fibres projecting into engagement with the sash and serving to both resiliently cushion the sash and reduce the sliding friction thereof.
13. A window channel comprising supporting side walls provided at their inner faces with a fabric carrying relatively long, closely arranged fibers projecting into en-

gagement with the window sash and serving to resiliently cushion the sash and reduce the sliding friction thereof.

14. A window channel comprising a fabric woven to form spaced pile surfaces having relatively long fibers projecting therefrom and also one or more substantially pile free surfaces intermediate said pile surfaces, said fabric being bent at said pile free surfaces into channel shape with said pile fibers resiliently supporting the sides of the window sash to cushion the same and reduce its sliding friction.

15. A window channel comprising a channel shaped supporting member and a relatively heavy fabric woven to form spaced pile surfaces having relatively long fibers projecting therefrom and one or more pile free surfaces intermediate said pile surfaces, said fabric being bent at said pile free surfaces into channel shape to line said supporting member, with said pile fibers resiliently supporting the sides of the window sash to cushion the same and reduce its sliding friction.

16. A window channel comprising a relatively heavy fabric woven to form three spaced pile surfaces having relatively long fibers projecting therefrom and also two substantially pile free surfaces intermediate said pile surfaces, said fabric being bent at said pile free surfaces into channel shape with said pile fibers resiliently supporting the sides and edges of the window sash to cushion the same and reduce its sliding friction.

17. A window channel comprising a channel shaped supporting member having the inner faces of its side walls lined with a fabric carrying relatively long closely arranged fibers projecting into engagement with the window to resiliently cushion the same and reduce the sliding friction thereof, said fabric having fiber-free marginal portions turned rearwardly over the outer edges of said channel side walls and secured on the outer side thereof.

CHARLES P. SCHLEGEL.
